UNITED STATES PATENT OFFICE.

ARTHUR S. ROBINSON, OF DAYTON, OHIO.

DRAG-LINE EXCAVATOR.

1,377,278.

Specification of Letters Patent. Patented May 10, 1921.

Application filed June 29, 1918. Serial No. 242,656.

To all whom it may concern:

Be it known that I, ARTHUR S. ROBINSON, a citizen of the United States, residing at Dayton, in the county of Montgomery and 5 State of Ohio, have invented a new and useful Improvement in Drag-Line Excavators, of which the following is a description.

My invention relates to drag-line excavators which consist essentially of a base supported by wheels or rollers carrying a circular frame containing conical wheels or rollers on which revolves a balanced platform supporting a boom and a mechanism including two drums for operating a hoist 10 or "bucket-line" and a pulling or "drag-line" respectively; which lines in turn are attached to a "bucket" or scoop which is filled or loaded by pulling or dragging the bucket toward the machine and backing 15 away from the excavated area, which, heretofore, has been the only method of operating drag-line machines. And the objects of my invention are:

First, without impairing the usefulness of 25 the machine as heretofore operated, to change the direction of the operation of the bucket.

Second, to enable the operator to fill 30 wagons, cars, hoppers, scows, etc., standing or situated on either or both sides and close to the machine.

Third, to enable the machine to operate 35 against a bank with an upward and outward movement of the bucket.

Fourth, to make it possible to excavate 40 ahead of the machine and move forward over the excavated area.

Fifth, when operated from the deck of a scow, to enable the machine to excavate a 45 channel ahead of the scow and move up over the excavated area.

Sixth, to unload scows and deposit the 50 material on docks or other scows, or on banks alongside of the machine.

Seventh, to excavate material on docks 55 or other locations and deposit on scows alongside of said docks and otherwise increasing the range of usefulness of drag-line excavators.

I attain these objects by constructing the main boom in the form of an A frame, and attaching an auxiliary or supplementary boom to the front of the revolving platform of a drag-line excavator between the 60 lower ends or legs of the main boom and independent of said main boom, as illustrated

in the accompanying drawings, in which my improvement, the auxiliary or supplementary boom, and as much of the elements of the A frame form of main boom as is necessary to provide for the operation of my auxiliary or supplementary boom, are shown in full lines, and the broken lines show the remainder of the main boom and other essential parts of the drag-line excavator. 65

Similar letters and numerals refer to similar parts throughout the several views.

Figure 1 is a side elevation of a drag-line excavator operating in the usual way and 70 illustrative of the prior art.

Fig. 2 is the side elevation of a drag-line excavator with the addition of my auxiliary or supplementary boom with the lower ends preferably hinged on the front end of the revolving platform, and the upper or outer 75 end suspended from the frames of the drag-line excavator and elevated at a suitable angle.

Fig. 3 is a horizontal view or plan of Fig. 2 showing my auxiliary or supplementary 80 boom situated between the legs and independent of the main boom and hinged to the front of the revolving platform or frame and its relation to the said main boom.

The position of the bucket at A is the filling 85 position; at B the carrying position and at C the dumping position in all views.

By building the main boom, 1, in the form of an A-frame with the lower ends placed at or near the corners, 2, of the upper or revolving frame of the drag-line excavator 3, there is formed an open triangular space between the legs of the main boom 1, and the front of the revolving frame 3. In my improvement the auxiliary 95 boom 4, preferably of the A-frame type, is placed within this space, having its lower ends preferably hinged to the front of the revolving frame 3, having the upper end supported, preferably by a flexible connection, from the main frame 6, or other suitable point, and having in its upper end 7, two sheaves, one sheave for the bucket-line 8, and one sheave for the drag-line 9, and operated by the drums 10 and 11 respectively. 100

In drag-line machines as heretofore operated, Fig. 1, the bucket-line 8, leads from the drum 10 to the outer end of the main boom 1, over a sheave 16, thence and fastened to 110 the bail 13, of the bucket 5, and the drag-line 9, leads from the drum 11, over the

guide sheave 15 to, and fastened to the bridle 14.

In my improvement Figs. 2 and 3, I accomplish the reversal of the direction of the bucket by carrying the bucket-line 8, from the drum 10, over one sheave at 7 in the auxiliary boom 4, and fasten it to the bail 13, of the bucket 5, and by carrying the drag-line 9, from the drum 11 over the other sheave at 7, in the auxiliary boom 4, thence to and over the sheave, 16, in the end of the main boom 1, thence to the bridle 14, of the bucket 5.

With my improvement the act of changing the direction of the operation of the bucket consists in changing the bucket-line 8, and the drag-line 9, from the positions shown in Fig. 1, to the positions shown in Fig. 2, and vice versa.

20 It is not essential that the bucket always be operated outwardly or away from the main frame as shown in Figs. 2 and 3, but the improved construction herein shown and described also permits the bucket to be operated inwardly in the usual direction with increased efficiency. In such construction, the bucket line or control line 8 will be carried over the sheave 16 and thence to the power plant, while the drag line 9 will be carried from the bucket over the sheave in the upper end 7 of the auxiliary boom, and thence to the power plant. In other words, the bucket would be merely reversed from the position shown in Figs. 2 and 3, and 35 when in reversed position the line 8 would be used as a drag line, and the line 9 as the bucket control line. This would enable the bucket to be dumped in close proximity to the power plant. By adjusting the auxiliary boom the dumping point may be varied to and from the main structure, so that the material may be dumped a greater or less distance away from the base of operation.

40 45 I am aware that, prior to my invention, drag-line excavators with main booms attached to the front of revolving platforms have been made. I therefore do not claim such a combination broadly; but what I do claim as my invention and desire to secure by Letters Patent is:

1. In a drag-line excavator the combination of a supporting structure, an auxiliary or supplementary boom, and a main boom, 50 said auxiliary or supplemental boom being extended to a point intermediate the terminal planes of the main boom, a scoop bucket and control cables therefor comprising a bucket line and a drag line separately controlled by said booms.

2. In a drag-line excavator, the combination of the A frame type of main boom with an auxiliary boom situated between the legs of the main boom, a scoop bucket and control cables therefor comprising a bucket line

and a drag line separately controlled by said booms.

3. In a drag-line excavator the combination of a supporting structure, an A frame type of main boom and an auxiliary boom 70 between the legs of the main boom, both booms being connected to the supporting structure, a scoop bucket and control cables therefor comprising a bucket line and a drag line separately controlled by said booms. 75

4. In a drag-line excavator the combination of a supporting structure, a main boom and an auxiliary or supplementary boom extending in overlapping relation from the supporting structure, a scoop bucket and 80 control cables therefor comprising a bucket line and a drag line separately controlled by said booms.

5. The combination of an auxiliary or supplementary boom, a main boom the supporting structure of a drag-line excavator, a bucket or scoop and operating cables therefor guided by said booms whereby the bucket or scoop is dropped substantially vertically from the auxiliary boom to a point adjacent 90 to the foot of the main boom and operated thence toward the tip of the main boom, substantially as and for the purposes set forth and described. 85

6. In a construction of the character described, a boom, a scoop, a drag line and a bucket line controlling the movement of said scoop, means for retrieving said lines, a guide for the drag line, a guide for the bucket line one of said guides being longitudinally adjustable in relation with the boom. 95

7. In a construction of the character described, a scoop, a drag line and a bucket line controlling the movement of the scoop, a 105 boom, a guide for one of said lines located adjacent to the end of the boom, and an adjustable guide for the other line from which the scoop may be dropped substantially vertically at different points intermediate the 110 foot and tip of the boom.

8. In a construction of the character described, a pair of booms arranged in overlapping relation and relatively movable in a common plane, a scoop, a drag line therefor 115 carried by one of the booms, and a bucket line therefor carried by the other boom, substantially as specified.

9. In a construction of the character described, a boom, a scoop, a drag line and a 120 bucket line, controlling the movement of the scoop and relatively adjustable guide elements for the drag line and the bucket line, spaced one from the other, one of said guide elements being adjustable to and from the 125 other element independent of the boom to different intermediate positions.

10. In a drag line excavator, the combination with a supporting structure of a main boom and an auxiliary boom both mounted 130

for oscillatory movement horizontally in unison, one boom being capable of oscillatory movement vertically independent of the other boom, a scoop, and separate cables connecting said scoop with each of said booms.

11. In a drag line excavator, the combination with a supporting structure, of two booms of different lengths extending upwardly and outwardly therefrom in overlapping relation, a scoop bucket, a drag line for the scoop bucket controlled by the longer boom, and a bucket line controlling the movement of the scoop bucket and in turn controlled by the shorter boom.
- 10 12. In a drag line excavator, the combina-

tion with a supporting structure of two relatively movable booms extending upwardly and outwardly therefrom, a scoop bucket, a drag line by which the bucket is actuated, carried by one of said booms, and a bucket line controlling the operation of the scoop bucket carried by the other boom.

In testimony whereof I have signed my name to this specification in the presence of two subscribing witnesses.
